Specification for Design.

Patented Feb. 3, 1914.

Application filed October 19, 1912. Serial No. 726,819. Term of patent 7 years.

To all whom it may concern:

Be it known that we, ANDREW J. McDONAGH and ALBERT E. WEBSTER, subjects of the King of Great Britain, residing at the city of Toronto, in the county of York, Province of Ontario, Canada, have invented a new, original, and ornamental Design for Tooth-Brushes, of which the following is a specification.

Referring to the accompanying drawings, Figure 1 is a side elevation. Fig. 2 is a plan

view, and Fig. 3 is an end view of a brush constructed in accordance with our design.

We claim—

The ornamental design for a tooth brush, as shown.

ANDREW J. McDONAGH.
ALBERT E. WEBSTER.
